United States Patent Office

Des. 207,453
Patented Apr. 18, 1967

207,453

POT COVER HOLDER

Louis Hoffman, 11 Paikin Drive,
Spring Valley, N.Y. 10977

Filed Mar. 7, 1966, Ser. No. 1,313

Term of patent 14 years

(Cl. D44—29)

Fig.1

Fig.2

Fig.3

Fig.4

Fig.5

I claim:

The ornamental design for a pot cover holder, substantially as shown.
